UNITED STATES PATENT OFFICE.

MILTON K. AKERS, OF TROY, OHIO, ASSIGNOR TO THE HOBART MANUFACTURING COMPANY, OF TROY, OHIO, A CORPORATION OF OHIO.

DESIGN FOR HOPPER FOR COFFEE GRINDERS OR THE LIKE.

Application filed November 3, 1923. Serial No. 7,676. Term of patent 14 years.

To all whom it may concern:

Be it known that I, MILTON K. AKERS, a citizen of the United States of America, residing at Troy, in the county of Miami, State of Ohio, have invented a new, original, and ornamental Design for Hoppers for Coffee Grinders or the like, of which the following is the specification, reference being had to the accompanying drawing, forming a part thereof.

The drawing shows an elevational view of

a hopper embodying this design which consists of a glass body having a base support and a top of contrasting material, the base and top, being preferably of polished metal, as shown.

I claim:

The ornamental design for hopper for coffee grinders or the like substantially as shown and described.

MILTON K. AKERS.
